[57] **CLAIM**

The ornamental design for a handrail bracket, as shown and described.

DESCRIPTION

FIG. 1 is a perspective view of a handrail bracket;
FIG. 2 is an elevational view of the handrail bracket;
FIG. 3 is a side elevational view of the handrail bracket;
FIG. 4 is a top plan view of the handrail bracket;
FIG. 5 is an elevational view of handrail bracket similar to FIG. 2, but taken in the opposite direction;
FIG. 6 is a bottom plan view of the handrail bracket;
FIG. 7 is a side elevational view of the handrail bracket in an upwardly bent position; and,
FIG. 8 is a side elevational view of the handrail bracket in a downwardly bent position.

The broken line showing of a portion of a handrail is for illustrative purposes only and forms no part of the claimed design.
